UNITED STATES PATENT OFFICE.

BENEDICT M. AULL, OF AUTUN, SOUTH CAROLINA.

BATHROOM RUG.

Application filed July 17, 1923. Serial No. 652,083.

To all whom it may concern:

Be it known that I, BENEDICT M. AULL, a citizen of the United States, residing at Autun, in the county of Anderson and State 5 of South Carolina, have invented a new and useful Bathroom Rug, of which the following is a specification.

The object of my invention is to provide a novel bath room rug or mat so made 10 that water when splashed on it will go through the pores and leave the top of the rug dry and not water soaked, as in the case of the average bath rug, and to provide a process for the rapid manufacture of my 15 rugs or mats. I attain these and other objects of my invention by weaving the rug in the manner or form illustrated in the accompanying drawings, in which—

Figure 1 is a perspective view of my invention;

Fig. 2 is an enlarged detail of a portion of one corner of same; and

Fig. 3 is a section on line 3—3 of Fig. 2.

Like numerals indicate like parts in each 25 of the several views.

Referring to the accompanying drawings, I weave the rug in two distinct layers or strips of open mesh leno weave, the top layer 1 resting loosely on the bottom layer 2. Near but spaced from the longitudinal 30 edges of the rug I interweave the top and bottom layers 1 and 2, respectively, in a close plain weave section 3 on opposite sides of the rug; and near but spaced from the ends 35 of the rug I interweave the top layer 1 and bottom layer 2 in a close plain woven transverse section 4, as shown in Fig. 1. I also interweave the top layer 1 and the bottom layer 2 in a plain close weave extending 40 along and forming the longitudinal edges of the rug 5, as shown in Fig. 1. I also interweave the ends of the rug and sew them across with a suitable type of stitching 6 to effectually prevent unraveling.

In the process of weaving the rug, 45 the top layer 1 and the bottom layer 2 are woven simultaneously in open mesh weave, the loom being adjusted to shift at the appropriate times to a close plain weave for weaving the reinforcing and ornamental 50 close woven sections 3 and 4.

The rug does not become watersoaked when in use as does the average bath room rug, which makes the usual bath rug very uncomfortable to stand on when it has become watersoaked. The open mesh weaving allows the water splashed on the rug to go through for the most part to the bottom layer, thereby increasing the usefulness of 55 the rug.

What I claim is:

1. A bath room rug comprising a plurality of layers of material woven in an open mesh leno weave, said layers having longitudinal and transverse sections interwoven 65 along the edges of the rug and at the ends thereof.

2. A bath room rug comprising a plurality of layers of material each woven in an open mesh leno weave, said layers having their 70 edge portions interwoven in plain weave to prevent unraveling, and having lines of stitching extending across the ends of the rug.

3. A bath room rug comprising like separate layers of material each layer being woven in an open mesh weave, means for preventing the edge portions of the rug from unraveling, the layers of material being interwoven in a close plain weave in sections extending longitudinally and transversely of the rug near but spaced from the edges thereof to reinforce the rug and increase its ornamental appearance.

BENEDICT M. AULL.
